US00D923641S

(12) **United States Design Patent** (10) **Patent No.:** **US D923,641 S**
Leach et al. (45) **Date of Patent:** **** Jun. 29, 2021**

(54) **DISPLAY SCREEN OR PORTION THEREOF WITH DIGITAL VISUAL CODE GRAPHICAL USER INTERFACE**

(71) Applicant: **Facebook, Inc.**, Menlo Park, CA (US)

(72) Inventors: **Christopher Anthony Leach**, San Carlos, CA (US); **Eugenio Padilla Garza**, San Francisco, CA (US); **Anthony Tran**, Sunnyvale, CA (US); **Russell William Andrews**, San Francisco, CA (US)

(73) Assignee: **FACEBOOK, INC.**, Menlo Park, CA (US)

(**) Term: **15 Years**

(21) Appl. No.: **29/719,454**

(22) Filed: **Jan. 3, 2020**

Related U.S. Application Data

(63) Continuation of application No. 29/677,613, filed on Jan. 22, 2019, now Pat. No. Des. 875,748, which is a continuation of application No. 29/574,394, filed on Aug. 15, 2016, now Pat. No. Des. 840,413.

(57) CLAIM

The ornamental design for a digital visual code graphical user interface for a display screen or portion thereof, as shown and described.

DESCRIPTION

The FIGURE is a front view of a display screen or portion thereof with digital visual code graphical user interface showing our new design.

The broken lines showing a display screen or portion thereof, computing device, and the remainder of the graphical user interface represent environment and form no part of the claimed design.

1 Claim, 1 Drawing Sheet
